UNITED STATES PATENT OFFICE.

ERNST KÖRTING, OF HANOVER, GERMANY.

PROCESS FOR HEATING AND FIRING BOILERS BY MEANS OF OIL.

No. 800,219.

Specification of Letters Patent.

Patented Sept. 26, 1905.

Application filed February 28, 1902. Serial No. 96,035.

To all whom it may concern:

Be it known that I, ERNST KÖRTING, a subject of the King of Prussia, German Emperor, residing at Hanover, Germany, (whose 5 post-office address is No. 2 Alleestrasse, Hanover, in the Kingdom of Prussia, German Empire,) have invented a certain new and useful Process for Heating and Firing Boilers by Means of Oil; and I do hereby declare that 10 the following is a full, clear, and exact description of the invention, which will enable others skilled in the art to which it appertains to make and use the same.

This invention relates to a process for heating and firing boilers by means of oil, and essentially consists in introducing the oil under pressure into a tube, heating the same in this tube to a point lying higher than that at which under atmospheric pressure vapors 15 would be developed, or its normal boiling-point, but lower than that point at which vapors are generated under the pressure the oil is subjected to, spraying the heated oil into the combustion-chamber and introducing air 20 into the spray within the combustion-chamber. It is evident that a considerable amount of vapor is developed when the heated oil under pressure is sprayed from the nozzles into the combustion-chamber and that by the generation 25 of vapor the small particles of sprayed oil are again so minutely disaggregated that they are completely burned in the current of air that is introduced into the spray.

In the accompanying drawings an oil-firing 30 is represented suitable for the new process, of which—

Figure 1 is a vertical longitudinal section, and Fig. 2 a section on the line 2 2 of Fig. 1.

The oil is forced by a pump *c* into the coil 35 *d* and from there into one or more nozzles *e*, opening into the combustion-chamber *b*. The coil *d* is arranged in a superheater *f*, into which the high-pressure steam serving as heating medium is supplied by a tube *g* and led off by tube *i*. In the steam-supply pipe 40 *g* a regulating-valve *h* is disposed for regulating the temperature up to which the oil is to be heated. In the front wall of the combustion-chamber *b* of the furnace are provided air-inlet 45 openings *l*, regulated by damper *m*, with apertures *n*. Around the spraying-nozzles *e*, and more especially around the air-inlet open-

ings *l*, a tapering ring *o* is arranged, by which the inrushing air is conducted to the oil-spray.

The oil to be introduced into the combustion-chamber is led under pressure into the coil *d* and in the same heated to a point lying higher than that at which the oil under atmospheric pressure would develop vapor, or its normal boiling-point, but lower than the 60 point at which vapors are generated under the pressure the oil is subjected to. The heated oil upon entering into the combustion-chamber will generate vapor, whereby the fine particles of oil formed by the action of the distributing or spraying nozzle *e* will be separated into minute parts. The fine oil-spray 65 mixes at once and intimately with the air-current passing in through the openings *l* and is conducted on the spray by the ring *o*, so that 70 a complete and smokeless combustion is insured.

What I claim, and desire to secure by Letters Patent of the United States, is—

1. The process of firing by means of oil, 75 which consists in heating the liquid oil unmixed with air or other gases to a point above its normal boiling-point, maintaining the oil in a liquid state by pressure while so heated and until delivered to the combustion-chamber, and then delivering the superheated liquid oil into a combustion-chamber supplied with air, whereby the rapid disintegration 80 and vaporization of the oil in the presence of air is secured, substantially as and for the 85 purpose stated.

2. The process of firing by means of oil, which consists in introducing liquid oil unmixed with air or other gases under pressure into a tube, heating the oil in the tube to a 90 point above its normal boiling-point but below the point at which vapors are generated under the pressure to which the oil is subjected, maintaining the oil in its liquid state by pressure until delivered to the combustion-chamber, and spraying the superheated liquid oil into a combustion-chamber supplied with air, substantially as and for the purpose stated. 95

3. The process of firing by means of oil, which consists in introducing liquid oil unmixed with air or other gases under pressure into a tube, heating the oil in the tube to a point above its normal boiling-point but below the point at which vapors are generated 100

under the pressure to which the oil is subjected, maintaining the oil in its liquid state by pressure until delivered to the combustion-chamber, spraying the superheated liquid oil 5 into the combustion-chamber, and introducing air into the spray, substantially as and for the purpose stated.

In testimony whereof I have hereunto set my hand in presence of two subscribing witnesses.

ERNST KÖRTING.
